(57) **CLAIM**

I claim, the ornamental design of a vinyl siding scoring tool, as shown and described.

DESCRIPTION

FIG. 1 is a top perspective view of a vinyl siding scoring tool with the adjustment stop forward, with magnified view of the utility knife slot, which is a cut in the main body with a width slightly larger than the blade on a utility knife.

FIG. 2 is a top perspective view of a vinyl siding scoring tool with the adjustment stop towards the rear of the tool, with magnified view of the utility knife slot.

FIG. 3 is a bottom perspective view of a vinyl siding scoring tool with adjustment stop towards the rear of the tool.

FIG. 4 is a top view.

FIG. 5 is a bottom view.

FIG. 6 is a left side view.

FIG. 7 is a right side view.

FIG. 8 is a front view (broken lines help show scoring gap); and,

FIG. 9 is a back view.
